(57) **CLAIM**

The ornamental design for an ampoule, as shown and described.

DESCRIPTION

FIG. 1 is a perspective view of the ampoule.

FIG. 2 is a side view thereof.

FIG. 3 is a front view thereof.

FIG. 4 is an opposite side view thereof.

FIG. 5 is a rear view thereof.

FIG. 6 is a bottom view thereof; and,

FIG. 7 is a top view thereof.

The broken lines are included for the purpose of illustrating portions of the ampoule that form no part of the claimed design.
